UNITED STATES PATENT OFFICE

2,161,819

CELLULOSIC CORD

Morris Katz, Bronx, N. Y.

Application February 4, 1938, Serial No. 188,692

9 Claims. (Cl. 57—150)

This invention relates to cellulosic cord produced primarily from such material as is commonly known as Cellophane; and the object of the invention is to economize on the construction of a cord or strand of this type while at the same time producing a finished product having greater luster or clearer color value than has been experienced with the production of devices of this kind, in accordance with methods here-
 tofore known; a further object being to provide a strand of the class described consisting of a cord upon which is twisted a plain colorless strip of Cellophane, and around which one or more strips of colored Cellophane are spirally wrapped and partially twisted in the production of the resulting cord or strand producing a single or multi-color effect on the resulting cord or strand; a still further object being to provide means for interlocking one edge of the outer strip with one edge of the inner twisted strip to more securely retain the strips one upon the other and to prevent unraveling thereof; and with these and other objects in view the invention consists in an article of manufacture of the class and for the purpose specified, which is simple in construction and efficient in use and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a detail view of a part of a strand made according to my invention and indicating the method of forming the same.

Fig. 2 is a view similar to Fig. 1 showing another form of construction.

Fig. 3 is a view similar to Figs. 1 and 2 showing another modification.

Fig. 4 is another view similar to Fig. 1 showing another modification; and,

Fig. 5 is a section substantially on the line 5—5 of Fig. 4.

In Fig. 1 of the drawing, I have shown one method of constructing a cord or strand according to my invention and, in this figure, 10 represents a core which may be composed of a thread, cord or other thin strand, which is preferably composed of rayon, and this core is also preferably saturated with any suitable material which will maintain the resulting cord soft and pliable for a relatively long period of time.

One method of treating the core is by passing the same through a tank containing water

and glycerine. At 11 is shown a fairly wide strip of plain or translucent cellulosic material, such as Cellophane, which is twisted about the core 10 to form an inner filler portion 11a; at 12 is shown an outer or finishing strip which is spirally wrapped or wound around the filler 11a in the operation of twisting the filler upon the core 10. The strip 12 is narrower than the strip 11 or, in other words, is of sufficient width to fully cover the filler 11a to produce on a resulting cord or strand 13 a color governed by the color of the strip 12, which is red in the construction shown. In this connection, it will be understood however that this strip may be of any desired color, or may be of a combination of colors. If the same should be produced in this manner, the filler 11a will be clear or colorless producing, when twisted, a silvery appearance upon a white core 10, and will produce in the resulting cord 13 a very high luster and clear color value of the color of the strip 12, that is to say, an outstanding sheen will prevail which is largely due to the silvery color value of the filler 11a formed from the transparent strip 11.

In Fig. 2 of the drawing, the core 10 and strip 11 will be the same as that shown in Fig. 1 in the production of the filler 11a, and substituted for the strip 12 are two narrow strips 12a and 14, the strip 12a being red, whereas the strip 14 is blue. In this construction, the resulting cord or strand 13a will have red and blue spirally arranged strips 15 and 16 thereon. In this connection, it will be understood that other combinations of colored strips may be employed depending entirely upon the effect to be produced, for example, red and green; black and orange, etc.

In Fig. 3 of the drawing, I have shown at 10, 11 and 11a the core and filler produced as in Fig. 1, and two narrow strips 12a and 14 similar to strips 12a and 14 of Fig. 2, except that the latter strips may be a trifle narrower than the strips shown in Fig. 2 and, in this construction, the resulting cords or strands shown in Fig. 3, by virtue of spirally wrapping the strips 12a and 14 thereof will produce three stripings on the resulting cord 13b, for example, a red strip 15a, a white strip 17 and a blue strip 16a to produce a red, white and blue cord, the silvery filler 11a producing the so-called white appearance in the strip 17 between the red and blue strips. Here again, it will be understood that other color values may be employed than those specified, and with this construction it is also possible to use

for the filler strip 11a, a colored strip instead of a transparent strip.

At this time, it is well to point out, however, that the purpose of utilizing the transparent filler strip 11a is not only to produce the increased luster and clear color value in the resulting cord but effects a material saving in the construction of the product. This will be understood when it is realized that, as a rule, cords of the type under consideration are made from, what is known as trimmings or end runs in the production of Cellophane sheets and, due to the fact that more transparent trimmings of this type are available than the colored trimmings, I have utilized for the main body of the cord a filler composed of this transparent material and have utilized a small quantity of the colored material to give the desired color to the resulting cord.

It will also be understood that the strips 12, 12a and 14 are not simply spirally wrapped upon the filler but are also twisted to a slight extent which aids in supporting the strips in position.

In Figs. 4 and 5 of the drawing, I have shown a slight modification of the construction shown in Fig. 1 and, in this figure, 10 represents a core similar to the core 10 and 11 a strip similar to the strip 11 but, in this construction, the outer or cover strip 18 has one edge 18a thereof flanged over one edge of the strip 11 so as to interlock the strip 18 with the strip 11 and, in this construction, a more secure binding is established between the strips 11 and 18, which will prevent the unravelling of the strip 18. The resulting cord and strand 19 will have darker stripings appearing thereon, where the flanged portion 18a prevails by virtue of the doubling of the material 18 upon itself, but the general color of the strip will be the same throughout but a more striped appearance will prevail, as is indicated in the shaded section at 20, in Fig. 4 of the drawing.

With the construction shown in Figs. 4 and 5 a greater twist will prevail in the strip 18 than in the construction shown in the other figures.

In addition to the advantages heretofore expressed, it will also be understood that a cord or strand made in accordance with the structure herein described and, as shown in Figs. 1 to 5 inclusive, you will have greater strength than other cords of this type made from a single strip arranged upon a core, and still greater flexibility is provided in the resulting cord by virtue of the spiral arrangement of the outer strip or strips.

It will be understood that the outer strips or strands may be printed or otherwise characterized to produce various two-tone or multiple color effects on a resulting cord. It is also possible to utilize a multiplicity of thin ribbons simultaneously wound upon the filler, in accordance with the teachings in Figs. 2 or 3 of the drawing.

In order to secure the outer sharp or strips to the inner or filler strip, I may use a suitable adhesive which may be applied to the filler prior to winding the outer strip or strips thereon, and this adhesive may be applied in spots or sections, if desired. On the other hand I may incorporate a suitable adhesive in the saturating solution applied to the core so that a part of the adhesive will penetrate, through the crevices of the filler and be exposed to the outer strip or strips for the purposes stated.

Having fully described my invention, what I claim as new and desire to secure by Letters Patent, is:

1. A cord or strand of the class described comprising a core, a twisted filler of "Cellophane" arranged on said core, and an outer covering strip of colored "Cellophane" spirally arranged upon said twisted filler. 5

2. A cord or strand of the class described comprising a core, twisted filler of "Cellophane" 10 arranged on said core, an outer covering strip of colored "Cellophane" spirally arranged upon said twisted filler, and said filler being formed from a strip of clear and colorless "Cellophane" and producing when twisted a filler body having 15 a silvery appearance.

3. A cord or strand of the class described comprising a core, a twisted filler of cellulosic material arranged on said core, an outer cellulosic covering strip spirally arranged upon said twisted filler, said filler being formed from a strip of translucent material and producing in the resulting filler body a silvery appearance, and said outer strip being interlocked with one edge of the 25 filler strip. 20

4. A cord or strand of the class described comprising a core, a twisted filler of clear and colorless "Cellophane" arranged on said core, and outer "Cellophane" strips of different colors 30 spirally arranged upon said filler. 35

5. A cord or strand of the class described comprising a core, a twisted filler of "Cellophane" arranged on said core, and an outer cellulosic strip of different colors spirally arranged upon said filler in such manner as to expose part of the filler through the resulting cord at spaced intervals longitudinally thereof. 40 35

6. A cord or strand of the character described comprising a rayon core, a twisted filler body of "Cellophane" on said core, an outer spirally arranged covering of cellulosic material of a color contrasting to the color of said filler, and said core being treated with a saturant maintaining the resulting cord soft and pliable. 40 45

7. A cord or strand of the character described comprising a rayon core, a twisted filler body of cellulosic material on said core, an outer spirally arranged covering of cellulosic material of a color contrasting to the color of said filler, said core being treated with a saturant maintaining 50 the resulting cord soft and pliable, and means interlocking the spiral strip with said filler. 55

8. A cord or strand of the character described comprising a rayon core, a twisted filler body of "Cellophane" on said core, an outer spirally arranged covering of "Cellophane" of a color contrasting to the color of said filler, said core being treated with a saturant maintaining the resulting cord soft and pliable, and the saturant including an adhesive adapted to penetrate 60 through said filler body to the covering material to bind the filler body and covering material together. 65

9. A cord or strand of the character described, comprising a rayon core, a twisted filler of "Cellophane" on said core and an outer spirally arranged covering of "Cellophane" of a color contrasting to the color of said filler, one edge of said cover strip being folded inwardly around the corresponding edge of said twisted filler and producing in said cord a multiple tone color effect. 70 75
